(57) **CLAIM**

The ornamental design for a pump for inflating tires, as shown and described.

DESCRIPTION

1. Pump for inflating tires

1.1 : Front

1.2 : Back

1.3 : Left

1.4 : Right

1.5 : Top

1.6 : Bottom

1.7 : Perspective

1.8 : Partial

1.9 : Partial

1.10 : Partial exploded

The design product name is pump for inflating tires; It is used to inflate various objects.

The broken lines shown in the drawings illustrate portions of the pump for inflating tires that form no part of the claimed design.
